FERDINAND FRANKE, OF PORT FULTON, KENTUCKY, ASSIGNOR TO FRED FRANKE & CO., OF LOUISVILLE, KENTUCKY, A PARTNERSHIP.

BAT-FORMING MACHINE.

1,243,058.

Specification of Letters Patent. Patented Oct. 16, 1917.

Application filed March 8, 1915. Serial No. 12,801.

To all whom it may concern:

Be it known that I, FERDINAND FRANKE, a citizen of the United States, residing in the city of Port Fulton, county of Clark, 5 and State of Kentucky, have invented certain new and useful Improvements in Bat-Forming Machines, of which the following is a specification.

This invention relates to machines for 10 felting fibrous material for use in making mattresses, with special reference to machines for handling linters and shoddy.

An object of the invention is to provide 15 a machine of the class described which will be economical in construction, efficient in service and require a minimum of supervision during its operation.

With the foregoing and other objects in view the invention has particular relation to 20 certain new and novel features of construction and arrangement of parts illustrated in the accompanying drawings which form a part of this specification, wherein is set forth an embodiment of the invention, but 25 it is to be understood that such changes and modifications may be resorted to as come within the scope of the claims appended hereunto.

Referring to the drawing, comprising two 30 sheets, wherein similar reference characters designate like parts in the several views; Figure 1, is a front elevation; Fig. 2, a rear elevation; Fig. 3, an end elevation, a portion of the base being broken away and the driving belts omitted; Fig. 4, a longitudinal section on line X—X of Fig. 3; Fig. 5, a plan of the front portion of the base; Fig. 6, an elevation of the forward portion, of the rear end of the carriage.

Referring now more particularly to the drawings the numeral —1— designates a 40 hopper provided for the reception of the fibrous material which is to be acted on. The hopper 1, comprises vertical side walls 45 —2— and upwardly diverging front and rear walls —3 and 4—, an inclined elevating belt —5— is positioned in the forward portion of the hopper and travels over rollers —6 and 7— mounted on shafts —8 and 9—. The rear wall of the hopper is mounted at its lower edge on a hinge —10—, and is adapted to be swung forward toward the elevating belt by a weight —11—, secured on the end of a rope —12— 50 which passes over a pulley —13— and is se-

cured to an arm —14— extended from the rear wall. The arrangement being such that the contents of the hopper are kept in constant contact with the elevating belt by the pressure of the rear wall. Transverse bat- 60 tens —15— attached to the rear edges of the sides 2 serve to restrain the backward move- 65 ment of the rear wall. A brush —16— at- 70 tached to a shaft —17— and positioned near the upper end of the elevating belt 5, on the rear side thereof, permits the passage of 75 only such fibers as are caught, or looped, about needles —18— which project from 80 said belt. Forward of shaft 9, is a trans- 85 verse shaft —19— from which extends beater arms —20— adapted to disengage the fiber from the needles 18. Above the upper end of the elevating belt is a flue outlet —101— from which a suitable connection 90 may be led to a suction fan for the purpose of drawing away dust. On one end of the beater shaft 19, exterior of the case, is a short crank —21— which is connected by means of a rod —22— with a long crank —23— on the end of the brush shaft 17; the 95 arrangement being such that while the beat- 100 ers are continuously rotated the brush 16 will receive a to and fro motion, due to the difference in length of the two cranks. When dislodged from the needles 18, by the 105 arms 20, the fiber falls on a horizontal feed belt —24— which carries it forward and presents it to the nip of feed rolls —25 and 26—. The belt 24 extends from a point in proximity to the belt 5, traveling 110 about shafts —28 and 29—, the arrange- 115 ment being such that any surplus material deposited on the belt will be seized by the needles in the belt 5 and returned to the hopper. The feed rolls 25 and 26, present the fiber to a picker cylinder —30—, mounted on a shaft —31—, which carries it through cards —32— and deposits it in a fleece on a carrier belt —33—. The carrier belt extends forward from the picker, in a 120 horizontal plane, within a casing —34—, the rear end of which is attached to a picker frame and the forward end supported by suitable means such as rods —35— which ex- 125 tend to an attachment with the ceiling. The 130 casing has an imperforate bottom —36— which extends from a point substantially even with the forward end of the carrier belt to a point adjacent the rear end thereof. The casing is also provided with a hood 135

—37— having a flue outlet —38— from which a suitable connection may be led to a suction fan (not shown) whereby the dust is carried away. The belt 33 travels about 5 rollers —39 and 40— mounted on shafts —41 and 42— positioned respectively in proximity to the picker cylinder 30 and near the forward end of the casing. On the belt are secured a plurality of spaced transverse 10 cleats —43—. As the fleece is deposited on the belt 33, heavy particles of dirt contained therein will fall between the cleats, and, as the belt turns under the forward roller, will be carried far enough to fall on the bottom 15 36 of the casing. Experience has shown that lint adheres to and is carried along by the larger particles of dirt and accumulating in the narrow spaces between the belt and the bottom, serves to brush the dirt to the rear 20 end where it falls off. The fleece drops from the forward end of the belt 33, through an outlet —44—, in a sheet the full width of the belt and is deposited across a carriage —50— in superimposed folds, or layers. 25 The carriage is movably supported upon a base —51— by wheels —52— and is adapted to be reciprocated thereon longitudinally relative to the belt 33. The base comprises side walls —53—, which serve as tracks for 30 the wheels 52, and end walls —54—. A shaft —55— positioned near the rear end of the base extends from the exterior to a point substantially in the center thereof, and is provided exterior of the base, with a pulley —56—, and on its inner end with a sprocket wheel —57—; a second sprocket wheel —58— carried on a bracket —59— is positioned forward of and in alignment with the first sprocket wheel. A sprocket chain —60— disposed about the sprocket wheels is driven by the first named wheel. A pitman rod —61— is pivotally connected at one end to a link of the sprocket chain, and at the other end to an arm —62— which depends from the forward end of the carriage. 45 The arrangement being such that when power is applied to the shaft 55, motion is imparted to the sprocket chain and through the medium of the pitman rod to the carriage 50 which will move in unison therewith, to, or fro as the link to which the pitman rod is connected may be above or below the axial line of the sprocket wheels. The carrier belt 33, is driven by a belt —96— 55 which extends from a pulley —97— on the shaft 55 to a pulley —98— on the shaft 42, the arrangement being such that the carrier belt and the carriage move at a uniform speed and consequently no strain is exerted 60 on the fleece as it is laid on the carriage. The carriage 50 comprises end frames —65— disposed transversely relative to the base 51 and the casing 34, in the lower corners of which are the supporting wheels 52. 65 A conveying belt —66— passes about rolls —67 and 68— which are journaled in the end frames, near the rear ends and spaced from the forward ends thereof respectively, the forward roll 68 being of greater diameter than the rear one. A winding roll —69— 70 secured on a shaft —70— is journaled in the frame in advance of and in horizontal alignment with roll 68. The diameter of the roll 69 is equal to that of the roll 68 and the added thickness of the belt 66. One end of 75 the journal of the roll 68 extends beyond the frame and bears a sprocket wheel —71—. Both ends of the shaft 70 extend beyond the frame and on one end is a sprocket wheel —72— which is in alignment with the 80 sprockets 71. A sprocket chain —73— disposed about the sprocket wheels 71 and 72 provides means whereby the winding roll 69 drives the belt 68 and they travel at a uniform speed. Means are provided for 85 driving the winding roll as follows: Levers —75 and 75'—, of the first class, are mounted on the shaft 70, next to the frame and beyond them are ratchet wheels —76 and 76'—. Pawls —77— and —77'— pivoted on 90 the levers, are adapted to engage with the ratchet wheels and advance them as the levers are moved. On the lower ends of the levers, forming prolongations thereof, are rollers —78 and 78'— which bear on adjustable rails —79 and 79'—. The rails 79 and 79' extend in a horizontal plane, from a central point on the inner face of the front wall of the base at an angle thereto, to connections with the end walls at points spaced 100 from the front wall. The rails 79 and 79' are preferably tubular and the inner ends are confined in a sleeve —105— which is secured to the forward side of the base. The outer ends of the rails rest in depressions —106—, in the ends of the base, and are retained therein by means of perforated plates —107—, the rails are held in adjusted positions by means of pins —108— which pass through perforations —110—, in the plates, 110 and slots —109— in the rails. As the carriage 50 moves in either direction, the upper ends of one of the levers 75 and 75' will be steadily advanced by the contact of the lower end with an inclined rail, and as a 115 pawl is engaged with a ratchet wheel the movement is communicated to the winding roll 69 and through the medium of the chain 73 to the belt 66. At the same time the other lever is being retracted by means of a spring —120—. It will be observed that the sheet of fiber coming from the carrier belt 33 encounters two movements, a longitudinal reciprocating movement of the carriage, as an 125 entirety, and a continuous transverse movement of the belt 66, with the result that the fleece is laid on said belt in diagonal overlapping folds, or layers. It is to be observed that the width of the folds, which is that of the finished felt, is governed by the 130

travel of the carriage which is controlled by the length of the chain 60. And that the thickness of the felt is dependent on the amount which the layers overlap and this is controlled by the inclination of the rails 79. The greater the inclination of the rails the greater the movement imparted to the belt 66 will be and the layers will be overlapped and consequently the thinner the felt, and conversely if the inclination of the rails is lessened. A pair of transverse rollers —81 and 82— are hung below the casing 34, one in front and the other in the rear of the outlet 44 in the bottom thereof. The rollers are so positioned that they will bear upon and compact the folds of fiber as deposited on the carriage. Rotatory movement, corresponding to the direction of the travel of the carriage, is imparted to the rollers by a driving rope —83— which passes about sheaves —84— and is attached to the opposite sides of the carriage. Power may be applied to the machine, from a suitable source, by means of a belt —85— which passes over a pulley —86— on the shaft 31. The elevating belt 5 is driven by means of a belt —87— which leads from a pulley —88— on the shaft 31 to a pulley —89— on the shaft 9. The feed belt 24 is driven by a belt —90— which leads from a pulley on shaft 9 to a pulley —91— on shaft 28. The feed roll 25 is driven by a belt —92— which leads from a pulley on shaft 28. The shaft 55 is driven by a belt —94— which leads from a pulley on shaft 31 to the pulley 56 on shaft 55. The beater shaft 19 is driven from the shaft 9 by means of spur gears —99—. It is understood that the machine is to be properly timed, that is the different pulleys and pinions are to be so proportioned that the different elements will travel at the proper speed to fulfil their several functions; this timing is well understood in the art. As the felt leaves the carriage belt it is rolled about a mandrel —102—, by the action of the winding roll 69 on the outside of the roll —103— (which is indicated by dotted lines) in a manner well known in the art. The mandrel is guided between brackets —104—.

It is thought that the construction and operation is so set forth in the foregoing that anyone skilled in the art pertaining thereto may make and use the same, and I claim:

1. In a bat forming machine, in combination, a reciprocating carriage, a conveyer belt thereon, means for depositing a web on said belt, a base on which said carriage is mounted, a pair of rails pivotally connected by one end to a central point on the inner face of wall of said base and extending therefrom in a horizontal plane to connections respectively with other walls at points spaced from said side wall, means actuated

by contact with said rails for moving the belt, and means for varying the angle of said rails relative to said walls to change the ratio of movement of the belt relative to the movement of the carriage. 70

2. In a bat forming machine, in combination, a reciprocating carriage, a conveyer belt thereon, means for depositing a web on said belt, a base on which said carriage is mounted, said base comprising side and end walls, an end wall having a recess in its upper edge, a rail pivotally connected by one end to a side wall and extended at an angle therefrom and disposed in said recess, a plate having a plurality of perforations secured over said recess and a pin adapted to be passed through a selected perforation to hold the rail in adjusted position, and means for moving said belt actuated by contact with the rail. 85

3. In a bat forming machine, in combination, a reciprocating carriage, a conveyer belt thereon, means for depositing a web on said belt, a base on which said carriage is mounted, a rail pivotally connected at one end to a side wall of said base, and extending at an angle therefrom in a horizontal plane to a connection with an end wall thereof, means for varying the angle of inclination of said rail with the side wall and means actuated by contact with the rail to advance the belt. 90

4. In a bat forming machine, in combination, a reciprocating carriage, a conveyer belt thereon, means for depositing a web on said belt, a base on which said carriage is mounted, a pair of rails pivotally connected by one end to a central point on the inner face of a wall of said base and extending therefrom in a horizontal plane to connections respectively with other walls at points spaced from said side wall and means actuated by contact with said rails for moving the belt. 105

5. The combination of a base having mounted thereon a reciprocable carriage carrying a conveyer belt, with means operable by movement of the carriage to impart continuous concurrent movement to said belt in determined ratio to the movement of the carriage, said means comprising a pair of rails connected by one end to a central point on an inner face of a wall of said base and extending therefrom in opposite directions to connections respectively with other walls at points spaced from said wall, a pair of levers mounted on and depending from the carriage and contacting respectively with said rails, and operative connections between said levers and the belt. 115

6. In a bat forming machine, in combination, a reciprocating carriage, a conveyer belt thereon, means for depositing a web on said belt, a base on which said carriage is mounted, said base comprising side and end 120

- walls, the end walls having elongated recesses in their upper edges, rails pivotally connected by one end to a side wall at a central point on the inner surface thereof and extending therefrom in a horizontal plane and resting respectively in said recesses, means for adjusting the position of the rails in the recesses to vary the angles of the rails relative to the side walls, and means actuated by contact with the rails to advance the belt.
7. In a bat forming machine a base comprising side and end walls, the end walls having elongated recesses in their upper edges, rails pivotally connected by one end to a side wall at a central point on the inner face thereof and extending therefrom in a horizontal plane and resting respectively in said recesses, in combination with means for feeding a bat, a carriage reciprocably mounted on said base, a movable belt on said carriage to receive said bat and means carried by said carriage adapted to be actuated by contact with said rails to impart continuous concurrent movement to said belt.
8. In a bat forming machine a base comprising side and end walls, the end walls having elongated recesses in their upper edges, rails pivotally connected by one end to a side wall at a central point on the inner face thereof and extending therefrom in a horizontal plane and resting respectively in said recesses, in combination with means for feeding a bat, a carriage reciprocably mounted on said base, a movable belt on said carriage to receive said bat, means carried by said carriage adapted to impart continuous concurrent movement to said belt by
- 15 6. and extending therefrom in a horizontal plane and resting respectively in said recesses, means for adjusting the position of the rails in the recesses to vary the angles of the rails relative to the side walls, and means actuated by contact with the rails to advance the belt.
- 10 7. In a bat forming machine a base comprising side and end walls, the end walls having elongated recesses in their upper edges, rails pivotally connected by one end to a side wall at a central point on the inner face thereof and extending therefrom in a horizontal plane and resting respectively in said recesses, in combination with means for feeding a bat, a carriage reciprocably mounted on said base, a movable belt on said carriage to receive said bat and means carried by said carriage adapted to be actuated by contact with said rails to advance the belt.
- 15 8. In a bat forming machine a base comprising side and end walls, the end walls having elongated recesses in their upper edges, rails pivotally connected by one end to a side wall at a central point on the inner face thereof and extending therefrom in a horizontal plane and resting respectively in said recesses, in combination with means for feeding a bat, a carriage reciprocably mounted on said base, a movable belt on said carriage to receive said bat, means carried by said carriage adapted to impart continuous concurrent movement to said belt by
- 20 9. In combination, a base, a reciprocably mounted carriage thereon, a conveyer belt carried by said carriage, a pair of rails pivotally connected by one end to a wall of said base at a central point thereof, and extending at an angle therefrom to adjustable connections with opposed walls extended from the first named wall, and means carried by the carriage and actuated by contact with said rails to advance said belt concurrently with and in determined ratio to the movement of the carriage.
10. In a device of the character described, a base, a reciprocating carriage thereon, a conveyer belt on said carriage, said base comprising side and end walls, a sleeve secured to the inner face of a side wall, the end walls having elongated recesses in their upper edges, said recesses being spaced from the aforesaid wall, a pair of rails having their inner ends disposed in said sleeve and their outer ends resting in said recesses, a plate disposed over each recess, said plates each having a plurality of perforations through selected ones of which a pin may be passed to hold the rail in adjusted position, and means carried by the carriage and adapted to be actuated by contact with the rails to advance said belt.

FERDINAND FRANKE.

MARGUERITE McALLISTER.

Copies of this patent may be obtained for five cents each, by addressing the "Commissioner of Patents,
Washington, D. C."

It is hereby certified that the residence of the patentee in Letters Patent No. 1,243,058, granted October 16, 1917, upon the application of Ferdinand Franke, for an improvement in "Bat-Forming Machines," was erroneously written and printed as "Port Fulton, Kentucky," whereas said residence should have been written and printed as *Port Fulton, Indiana*: and that the said Letters Patent should be read with this correction therein that the same may conform to the record of the case in the Patent Office.

Signed and sealed this 14th day of May, A. D., 1918.

[SEAL.]

R. F. WHITEHEAD,

Acting Commissioner of Patents.
